United States Patent Office

Des. 180,203
Patented Apr. 30, 1957

180,203

CHAIR BASE OR SIMILAR ARTICLE

Samuel M. Shone, Los Angeles, Calif.

Application December 19, 1955, Serial No. 39,388

Term of patent 14 years

(Cl. D15—1)

FIG.-1-

Fig. 1 is a front view of a chair base of this invention;
Fig. 2 is a side view of the chair base shown in Fig. 1;
and

Fig. 3 is a perspective view of the chair base shown in
Fig. 1 looking upwards from the bottom of this chair base.

I claim:

The ornamental design for a chair base or similar article, substantially as shown.
